Primary Examiner — Susan E Krakower(74) *Attorney, Agent, or Firm* — Ohlndt, Greeley, Ruggiero & Perle, L.P.(57) **CLAIM**

The ornamental design for a two petal teether, as shown and described.

DESCRIPTION

FIG. 1 is a front, perspective view of the two petal teether according to the present design;

FIG. 2 is a front elevation view of the two petal teether of FIG. 1; the opposite side of the two petal teether being a mirror image of this front elevation view;

FIG. 3 is a right side view of the two petal teether of FIG. 1; the opposite side view of the two petal teether being a mirror image of the right side view;

FIG. 4 is a top view of the two petal teether of FIG. 1; and, FIG. 5 is a bottom view of the two petal teether of FIG. 1. The broken lines illustrate portions of the two petal teether which forms no part of the claimed design.
